Des. 236,850
Patented Sept. 16, 1975

236,850

CONTROL PANEL FOR A COPIER

Ruediger W. Knott, Rochester, N.Y., assignor to
Xerox Corporation, Stamford, Conn.

Filed Mar. 16, 1973, Ser. No. 342,241

Term of patent 14 years

Int. Cl. D16—03

U.S. Cl. D61—1 Q

FIG. 1

FIG. 2

FIG. 3

FIG. 4

FIG. 5

FIG. 6

FIG. 1 is a right side perspective view of a control panel for a copier showing my new design with the right side panel fragmented to show additional controls;

FIG. 2 is a front elevational view thereof;

FIG. 3 is a top plan view thereof;

FIG. 4 is a bottom plan view thereof;

FIG. 5 is a rear elevational view thereof; and

FIG. 6 is a left side elevational view thereof.

I claim:

The ornamental design for a control panel for a copier, substantially as shown and described.
